CORPORATION OF OHIO.

CIGAR-BUNCHING MACHINE.

Application filed June 17, 1922. Serial No. 569,052.

Our invention relates to cigar bunching machines generally and particularly to certain improvements in machines of this type now universally in use. Generally speaking 5 a cigar bunching machine comprises a tobacco hopper, a matrix slide by which the filler is taken from the hopper in measured quantities and presented before a rolling table, a plunger by which the filler is discharged 10 from the matrix into a pocket formed by the rolling apron, means for operating the rolling apron to form the bunch, a bunch carrier into which the apron discharges, a mould carrier supporting a mould to which 15 the bunch is presented by the bunch carrier and means for discharging the bunches from the bunch carrier into the mould.

Our present invention has for its objects 20 to improve the construction of some of the parts of the machine and to add features thereto which will not only improve the operation of the machine but also the finished article produced thereby.

One improvement forming the subject 25 matter of our present invention is the material feeding mechanism. Heretofore difficulty has been experienced in positively feeding the tobacco to the matrix in uniform amounts and our invention is designed to 30 overcome such deficiencies encountered in mechanisms heretofore used.

The material is placed in a hopper or container and is fed horizontally by a pair of screws driven by a suitable driving mechanism. 35 Because of the inconsistent nature of the material we provide adjacent the delivery ends of the screws a pair of wings or arms which are adapted to oscillate, thereby shaving off the material which clings within 40 the screws. These oscillating arms or wings preferably derive their motion from the reciprocating plunger usually employed to eject the filler from the matrix onto the rolling apron. The reciprocating arm carries 45 a pair of rollers which cooperate with a pair of slotted arms formed on the oscillating wings or arms whereupon reciprocation of the arm oscillates the wings and produces the desired uniformity in feeding of the 50 material.

Another feature of our improved structure relates to the construction of the matrix or measuring device. In cigar bunching machines a matrix is mounted for re-

ciprocalation beneath the hopper and is provided with an aperture into which the tobacco from the hopper is forced. Heretofore however it has been difficult, owing to the inconsistency of the tobacco, to fill the aperture or shaping cup of the matrix uniformly. Particularly is this so when the shaping cup is of small dimensions as in this case the material has a tendency to arch across the smaller portions of the aperture resulting in an inconsistent density of the 55 material throughout the shaping cup.

Therefore our invention contemplates the provision of a matrix or measuring device of such a construction whereby the width of the aperture, when the measuring device is 60 ready for filling, may be increased so that the material forced therein may readily find its way into all parts of the matrix. Thereafter the size of the aperture will be decreased to its normal size thereby insuring 65 a uniform compactness of the material contained therein.

Our improved structure further contemplates the provision of what is known as a 70 binder stretcher or binder smoother. In cigar bunching machines the binder is usually placed upon the bunch rolling table and means provided for stretching the binder during the rolling operation. However 75 mechanisms heretofore used have proven inefficient due to the fact that they tended to tear or mutilate the binder and to move the binder from its proper position which caused the bunch to be incorrectly rolled.

Our invention therefore contemplates the 80 provision of a binder stretcher mechanism which includes a revolving brush which will smooth the binder and stretch the same without tearing or mutilating it. Furthermore the construction of the binder stretcher 85 mechanism is such that it is automatically moved away from the rolling table thereby giving the operator unhampered access to any part of the rolling table so that the binder may be easily and conveniently placed in its proper position upon the table. Furthermore the arrangement of the parts 90 is such that the brush is brought down upon the binder at an early stage of the rolling operation thereby operating efficiently in 95 cases where small binders are used.

In cigar bunching machines a mechanism is employed which is known as a bunch car-

rier and has for its purpose to catch the bunch after it has been rolled and to convey it to a convenient position for depositing it into the mould. Heretofore mechanisms 5 of this type have been inefficient because they were slow to close after receiving the bunch, thereby permitting the binder to loosen from the filler and also by reason of the fact that they necessarily held the bunch 10 so tightly at the moment when it was being deposited into the mould, that the binder was injured because of the friction of the carrier on the bunch and because of the pressure of the plunger which was necessary 15 to push the bunch through the carrier into the mould.

Therefore it is an object of our invention to form the carrier of a pair of spring jaws under tension together with means whereby 20 they are opened at the time the bunch is discharged from the rolling table into the jaws and whereby the spring jaws instantly clamp the bunch after it is deposited therein, thereby preventing the binder from un- 25 ravelling and giving the bunch a smooth uniform appearance. Furthermore our structure contemplates the provision of means whereby the spring pressure of the 30 jaws is released at the instant the plunger ejects the bunch from the jaws into the mould, thereby eliminating a large amount of the frictional resistance usually offered to the bunch at the moment of its ejection. Consequently need for excessive pressure of 35 the plunger for ejecting the bunch from the jaws into the mould is eliminated and the tearing of the binder at the point where the plunger comes in contact therewith is prevented. 40 With the foregoing objects in view our invention consists in the novel arrangement and construction of parts which will be made more apparent hereinafter in the accompanying specification and claims and in 45 the drawings wherein:—

Fig. 1 is a perspective view of a cigar bunching machine embodying our improved features,

Fig. 2 is an enlarged fragmentary per- 50 spective view showing some of the parts in dotted line position,

Fig. 3 is a fragmentary side elevation of the machine showing the bunch discharging into the bunch carrier,

Fig. 4 is a fragmentary side elevation showing the bunch being deposited into the mould,

Fig. 10 is a fragmentary side elevation of the rolling table showing the binder 70 stretcher mechanism in one extreme position,

Fig. 11 is a similar view showing the binder stretcher in its starting position,

Fig. 12 is a detailed perspective view of one of the jaws of the binder carrier, and 75

Fig. 13 is a fragmentary top plan view of the rolling table.

While we have illustrated the improvements which form the subject matter of this present application as applied to a particular type of cigar bunching machine it should be understood that we do not wish to be unnecessarily limited and thereby reserve the right to embody these improvements in any of the cigar bunching machines now on the market and to which these improvements may be applicable.

For further detailed description of the construction and operation of this general type of cigar bunching machine reference 80 is hereby made to United States Patent No. 672,096 dated April 16th, 1901.

The reference character 20 represents a hopper formed with a bottom discharge opening 21, suitably mounted upon the 85 frame 22 of the machine. This hopper is open at its upper side and is designed to receive in the present instance tobacco for forming the fillers of cigars or the like.

Rotatably mounted within the hopper 20 on shafts 23 are a pair of screws 24 which are designed to convey or feed the material toward the discharge opening 21. Mounted adjacent the front or delivery ends of the 100 screws 24 is a pair of oscillating wings or arms 25 whose purpose it is to shave off the material fed by the screws 24. These wings are formed integrally with or rigidly secured to sleeves 26 which extend through the front of the hopper 20 and are journaled 105 therein. These sleeves receive and support the forward ends of the shafts 23. Secured to the sleeves upon the ends which project outside the hopper 20 is a pair of arms 27 formed with slots 28 extending to one end thereof. Secured to a reciprocating arm 69 110 (hereinafter referred to) is a bridging member 29 which carries a pair of stud rollers 30 which rollers are adapted to enter the slots 28 and move longitudinally therethrough. 115 (See particularly Fig. 2.)

As the arm 69 reciprocates the slot arms 27 will be oscillated and through the medium of the sleeves 26, will oscillate the wings 25 to slice off the material which clings upon the forward end of the screws 24.

Adjacent the front end of the hopper is a plunger 32 carrying a tamper 33, which plunger and tamper reciprocate inside the 120 hopper 20 to eject the material through the 125

discharge opening 21. This tamper mechanism is of the construction now generally employed.

justable lock nuts 59 which in one position abut the lugs 56 shown clearly in Fig. 7.

Mounted immediately over the stationary

Any suitable mechanism may be employed for rotating the screws 24 and for reciprocating the tamper and plunger arm and as this specific mechanism forms no important part of our present invention we will only briefly refer to the same. For 10 rotating the screws 24 there would preferably be keyed to the rear end of the shafts 23 gears 34 which intermesh as clearly shown in Fig. 5, one of which gears would have power applied thereto by a pinion gear 35 15 keyed to a power shaft 36 operated in some suitable manner from the power shaft of the machine. For reciprocating the tamper and plunger arm we would preferably employ a mechanism similar to that illustrated 20 in United States Patent No. 1,002,655 dated September 5th, 1911, in which a rocker arm 37 is pivotally connected intermediate its length to a bracket 38 secured to the hopper 20, the forward end of the rocker arm 37 25 being pivotally connected as at 39 to the upper end of the plunger 32. The rear end of the rocker arm 37 being pivotally connected as at 40 to a vertically reciprocating arm 41 the lower end of which carries a 30 roller 42, which arm is normally pressed downwardly by a spring 43 bearing on the one end against a collar 44 and on the other end against the bracket 38. A cam wheel 44 connected to the power shaft of the machine and provided with a series of cam surfaces 45 periodically acts upon the rod 41 to successively shift the same against the action of the spring 43 whereupon a series 35 of reciprocation is imparted to the tamper plunger 32 and the bridging member 29. 40

side 49 of the shaping cup is a knife or blade 60 secured thereto by bolts or the like 70 61. Secured to the underside of the hopper 20 and adjacent the edge of the discharge opening 21 and cooperating with the knife 60 is a second blade or knife 62. These knives are adapted to shear off the surplus tobacco as the matrix moves towards its discharging position, part of which surplus material has bulged up when the matrix has been contracted. 75

In Fig. 7 the shaping cup or opening 48 is indicated in its greatest maximum open position and this is accomplished by reason of the matrix receding, the movement of the bar 52 and the tumblers being arrested when the lock nuts 59 engage the lugs 56. 80 In this manner the matrix body 46 continues to recede, at the same time stretching the springs 57. In this position the opening or shaping cup 48 is positioned beneath the discharge opening 21 of the hopper 20 and when a charge of tobacco has been deposited in the opening 48 the matrix is then moved forward or toward the left as viewed in Fig. 6 so as to position the opening 48 of the matrix in its discharging 85 position. On the forward movement of the matrix 46 the rigid wall 49 thereof continues its movement toward the side formed by the tumblers 50 until the end pieces 63 engage the bar 52, whereupon the opening 48 has been reduced to its minimum size and the tobacco therein has been suitably compressed. Obviously the knives or blades 60 and 62 cooperate to shear off the excess tobacco which has been deposited in the open- 90 95 100

Slidably disposed beneath the hopper 20 is a matrix 46 guided in side guides 47 formed on the machine. The matrix is formed with an opening or shaping cup 48 provided with a rigid side wall 49 and a side wall composed of a plurality of independently adjustable sections in the form of tumblers 50. The independent adjustment of the tumblers 50 is accomplished by bolts 51 which pass through a bar 52 and into the tumblers 50 and are provided with heads 53 and lock nuts 54. By properly adjusting any of the bolts 51 the associated tumbler may be advanced toward or moved away from the rigid wall 49 and the shape and size of the shaping cup varied accordingly. The tumblers are locked in position by the lock nuts 54.

Permanently attached to the bar 52 at each end thereof is a rod 55 which rods pass through bearing lugs 56 formed upon the frame 47. The other end of the rods 55 are connected by means of coil springs 57 to pins or lugs 58 projecting from the side of the matrix. The rods 55 also carry ad- 60 Red by an arm 69 which is reciprocated at the proper time to deposit the filler in the pocket adjacent the edge of the rolling table. 125 The rolling table is indicated by the reference character 70.

justable lock nuts 59 which in one position abut the lugs 56 shown clearly in Fig. 7.

Mounted immediately over the stationary side 49 of the shaping cup is a knife or blade 60 secured thereto by bolts or the like 61. Secured to the underside of the hopper 20 and adjacent the edge of the discharge opening 21 and cooperating with the knife 60 is a second blade or knife 62. These knives are adapted to shear off the surplus tobacco as the matrix moves towards its discharging position, part of which surplus material has bulged up when the matrix has been contracted. 70 75

In Fig. 7 the shaping cup or opening 48 is indicated in its greatest maximum open position and this is accomplished by reason of the matrix receding, the movement of the bar 52 and the tumblers being arrested when the lock nuts 59 engage the lugs 56. In this manner the matrix body 46 continues to recede, at the same time stretching the springs 57. In this position the opening or shaping cup 48 is positioned beneath the discharge opening 21 of the hopper 20 and when a charge of tobacco has been deposited in the opening 48 the matrix is then moved forward or toward the left as viewed in Fig. 6 so as to position the opening 48 of the matrix in its discharging position. On the forward movement of the matrix 46 the rigid wall 49 thereof continues its movement toward the side formed by the tumblers 50 until the end pieces 63 engage the bar 52, whereupon the opening 48 has been reduced to its minimum size and the tobacco therein has been suitably compressed. Obviously the knives or blades 60 and 62 cooperate to shear off the excess tobacco which has been deposited in the opening 48 and also that which has bulged up by reason of the reduction of size of the opening. Thus the density of the charge in the shaping cup 48 is uniform and consistent.

For reciprocating the matrix 46 there may be provided a pair of lugs 64 to which is pivotally mounted a link 65 connected to an arm 66 operated by a suitable cam on the drive shaft of the machine.

Referring now more particularly to Figs. 2, 5, 6, 10, 11 and 13, the binder stretcher mechanism will be described.

As the matrix 46 is moved forward it is positioned over a pocket formed by a die 66^a and an apron 67. The filler is ejected from the opening 48 by a plunger 68 carried by an arm 69 which is reciprocated at the proper time to deposit the filler in the pocket adjacent the edge of the rolling table. The rolling table is indicated by the reference character 70.

Rigidly secured to the frame of the machine is a cam plate 71 provided with a recess or depression 72 and a cam surface 73. 130

Rigidly secured to the cam plate 71 and projecting downwardly at an angle therefrom is an arm 74 to the other end of which there is pivotally connected as at 75 a rocking cam 5 76. The lower end of the rocking cam 76 normally rests on a bumper strip 77 secured to the cam plate 71 and the movement of the rocking cam 76 is limited in the other direction by a stop 78. Both the bumper strip 77 10 and the stop 78 may be of a resilient nature so as to eliminate unnecessary noise. 79 indicates (see particularly Figs. 6, 10 and 11) a plate projecting from the hopper 20 through which the plunger 68 projects.

15 The reference character 80 indicates a pair of rocker arms pivoted to the frame of the machine so as to swing about the same center as that of the arc of the surface of the rolling table. The ends of the respective 20 rocker arms have bearings 81 which support a shaft 82 which carries a roller 83 over which the apron 67 is adapted to pass.

The rocker arms 80 support the binder stretcher mechanism by means of right and 25 left hand supports 84 which are secured rigidly thereto by means of bolts 85. Each support 84 is formed with a lug upon which the binder stretcher frame 86 is pivotally secured as at 87. The frame 86 at one side 30 thereof is provided with an arm 88 carrying a stud roller 89. Supported in suitable bearings 90 carried by the frame 86 is a brush shaft 91 which carries a brush 92. The end 35 of the brush shaft 91 carries a pulley 93 while the end of the shaft 82 is provided with a pulley 94. An elastic belt 95 passes around the pulleys 93 and 94 and over an idler pulley 96^a carried by the frame 86. Thus when the shaft 82 rotates this rotary 40 motion is transmitted to the brush shaft 91 thereby rotating the brush.

Each support 84 has affixed thereto lugs 96 which support adjusting bolts 97 which engage bumper blocks 98 which may be of a 45 resilient nature. Thus by adjusting the bolt 97 the height of the rotating brush may be regulated and consequently the pressure the brush exerts upon the binder. These bolts 97 furthermore regulate the movement of the 50 frame 86 and brush 92 so as to keep the stud roller 89 in position to engage the rocking cam 76.

With the parts in the position illustrated 55 in Fig. 11, that is with the stud roller 89 resposing in the cam recess 72, the frame 86 is swung about its point of pivotal suspension 87 so that the brush 92 is raised away from the table and clears the projection 79. As the rocker arms 80 move forward over the 60 table with the roller 83 to roll the bunch B which had previously been deposited in the pocket formed in the die 66^a, the binder stretcher frame 86 is moved away from the cam plate 71 and consequently the stud roller 65 89 rides out of the recess 72 and on the cam

face 73. The shape of this cam face is such that the brush 92 is permitted to quickly descend upon the table 70 in advance of the roller 83. As is customary in these machines a binder has been previously laid upon the 70 table and therefore the brush 92 bears upon the binder immediately in front of the filler around which the binder is being wrapped. Owing to the movement of the apron 67 the roller 83 is being rotated and consequently 75 the shaft 82 whereupon the rotary motion is applied to the brush 92 through the medium of the pulleys 94 and 93 and the elastic belt 95. This rotary motion of the brush smooths the binder and exerts enough 80 pressure on it to stretch the same. As hereinbefore mentioned the pressure exerted by the brush 92 may be regulated by adjusting the bolts 97. As the binder stretcher frame moves toward the end of the table the stud 85 roller 89 engages the rocking cam 76 and during the continued movement of the frame rocks the rocking cam 76 so that the stud roller 89 may clear the upper end thereof. As the stud roller 89 clears the upper end of 90 the rocking cam 76 this cam assumes by gravity the position illustrated in Fig. 10. Upon the return movement of the binder stretcher frame the stud roller 89 engages the under side of the rocking cam 76 and rides along the same. As the stud roller 89 passes the point 75 of pivotal connection of the 95 rocking cam it raises the said cam to the position illustrated in dotted line in Fig. 10 that is until the rocking cam 76 abuts the stop 78. In this position the rocking cam directs the stud roller 89 into the recess 72 whereupon the rocking cam 76 again drops by gravity to the position illustrated in full 100 lines in Fig. 10. Obviously with the stud roller 89 again reposing in the recess 72 the binder stretcher frame together with the brush is moved up clear of the table 70 so that the operator can conveniently place a new binder upon the table ready for the next 105 operation. The ends of the apron 67 are preferably attached to a pair of controlling levers 98^a and 99 suitably controlled by cams on the power shaft of the machine.

110 As hereinbefore mentioned after the rotating brush 92 has dropped upon the binder it moves forward relatively in advance of the bunch being rolled, smoothing the binder and holding it taut, thus giving the bunch a smooth uniform appearance.

115 As the apron 67 rolls the bunch to the edge of the table 70 it is discharged therefrom and caught by what is known in the art as a bunch carrier, which conveys the bunch to a convenient position for depositing it in the mould. This bunch carrier must grasps the bunch immediately so as to prevent the same from unravelling.

120 The bunch carrier consists of a stationary jaw 100 formed integrally with a slide 101

which moves in a horizontally disposed slideway 102, the reciprocatory movement of which is accomplished by means of a link 103 suitably actuated by a lever 104 controlled by a cam on the power shaft of the machine. Cooperating with the stationary jaw 100 is a movable jaw 105 formed with a shaft 106 which is mounted in the bearing 107 carried by the stationary jaw 100. Spring means such as the coil spring 108 is provided which exerts a pressure tending to move the jaw 105 to a horizontal position and toward the stationary jaw 100. A bumper block 109 is formed upon the movable jaw 105, one portion of the bumper block 109 being cut to form a cam surface 110.

One of the rocker arms 80 has mounted thereon a bumper pin 111 which is adjustably held by a lock nut 112. The bumper pin 111 is adapted to engage the bumper block 109 as the arm swings over the edge of the rolling table 70. Thus just prior to the time that a bunch is discharged into the jaws 100—105 the bumper pin 111 engages the bumper block 109 and swings the movable jaw 105 from the stationary jaw 100 and against the tension of the spring means 108, thereby enabling the bunch to be easily deposited between the jaws. However the movement of the arm 80 is immediately reversed and the movable jaw 105 permitted to again move toward the stationary jaw 100 whereupon the bunch is caught and positively held thereby preventing an unravelling of the same.

In the operation of the machine the jaws 100—105 move toward a mould 112^a which is successively fed step by step to present the mould recesses 113 beneath the bunch carrier 100—105. Thereupon a plunger 114 carried by an arm 115 and reciprocated by suitable mechanism is adapted to eject the bunch from the bunch carrier into the mould recess disposed thereunder. The plunger 114 has formed thereon a finger 115 which acts as a cam and cooperates with the cam surface 110 formed on the block 109. The position of the finger 115 is such that it engages the cam surface 110 just prior to the time the plunger 114 engages the bunch B so that the movable jaw 105 is moved away from the stationary jaw 100 thereby permitting the bunch B to be ejected from between the jaws without necessitating any considerable amount of pressure and eliminating the possibility of tearing or injuring the bunch.

Obviously therefore means are provided whereby the bunch carrier is open just prior to its reception of the bunch and closes immediately so as to properly hold the bunch and prevent the binder from unravelling. Furthermore it is obvious that just prior to the ejection of the bunch from be-

tween the jaws and into the mould the jaws are again moved apart so that the bunch and binder will not be injured by friction and an excessive pressure need not be exerted by the plunger 114 in ejecting the bunch.

As hereinbefore mentioned the operation of the machine as a whole has been described only in so far as its operations effect the improvements forming the subject matter of our present invention. The manner of operation of cigar bunching machines is well known and the physical embodiment of the machine illustrated herein is believed sufficient to enable those skilled in this particular art to understand the features and advantages of our improvements.

It should be understood that the physical embodiment of the cigar bunching machine disclosed herein is for illustrative purposes only and that our improved features are applicable with equal efficiency to many varied types of bunching machines now in use. In operation our invention contemplates the provision of a feeding means for efficiently discharging the material from a hopper, a matrix or measuring device constructed so as to insure uniform density of material in the shaping cup thereof, a binder stretcher and smoother which will efficiently act in the case of small or large binders and will in one position be clear of the rolling table whereby the operator may conveniently place a new binder on the rolling table and lastly a bunch carrier so arranged as to handle the bunch properly and efficiently to eliminate possible injury thereto.

The specific structure of the improvements forming the subject matter of our invention may also be varied so as to accommodate them to various types of machines and to particularly adapt them for accomplishing the problem at hand and to this end we reserve the right to make such changes and modifications in the form thereof as may come within the purview of the accompanying claims.

Having thus described our invention what we claim is:

1. Tobacco feeding means comprising a hopper having a discharge opening adjacent the bottom of the hopper and also adjacent one side thereof, a pair of rotatable screws presented towards said discharge opening for urging the tobacco towards said opening and oscillating means adjacent the end of said screws for disengaging the tobacco therefrom.

2. Tobacco feeding means according to claim in which the rotatable screws are disposed side by side near the bottom of the hopper and extend substantially from end to end and from side to side of the hopper, whereby the entire mass of tobacco

in the lower part of the hopper is brought under the influence of said screws.

3. Tobacco feeding means comprising a hopper having a discharge opening, one or 5 more rotatable screws in said hopper for urging the tobacco toward said discharge opening, and means adjacent the discharge end of said screw or screws for disengaging tobacco from said screw or screws.

10 4. Tobacco feeding means comprising a hopper having a discharge opening, one or more rotatable screws in said hopper terminating adjacent said opening for urging the tobacco toward said opening, and shearing 15 means movable transversely across the discharge end of said screw or screws for disengaging tobacco from said screw or screws.

5. Tobacco feeding means according to 20 claim 4 in which the shearing means comprises an oscillating wing for each screw.

6. Tobacco feeding means comprising a hopper having a discharge opening, one or 25 more rotatable screws in said hopper terminating adjacent to and above said opening, and shearing means movable transversely across the discharge end of said screw or screws for disengaging tobacco from said screw or screws and causing it to fall into said opening.

30 7. Tobacco feeding means comprising a hopper having a discharge opening, one or more rotatable screws in said hopper terminating adjacent to and above said opening, shearing means movable transversely 35 across the discharge end of said screw or screws for disengaging tobacco from said screw or screws, and causing it to fall into said opening, a plunger for forcing tobacco through said opening, and means actuating said shearing means and said plunger in timed interrelation.

40 8. In a cigar bunching machine the combination of a measuring device having a 45 shaping cup, means for feeding tobacco to said shaping cup, means for moving said measuring device into and out of registry with said tobacco feeding means, said shaping cup having a rigid side wall and another side wall displaceable with respect

to said rigid wall, resilient means tending 50 to close the interval between said walls, and a stop limiting the movement of said displaceable wall as the measuring device moves into registry.

9. In a cigar bunching machine in combination, a bunch carrier comprising a pair of relatively movable jaws, means for delivering a bunch between said jaws, means tending to normally close said jaws, bumper pin means for opening said jaws prior to 60 the deposit of said bunch, and means for opening said jaws prior to the ejection of the bunch from said jaws.

10. In a cigar bunching machine in combination, a bunch carrier comprising a pair 65 of relatively movable jaws, spring means tending to close said jaws, means for delivering a bunch between said jaws, and means responsive to said delivering means for opening said jaws at the time of delivery and 70 permitting said jaws to close immediately after the bunch has been received.

11. In a cigar bunching machine in combination, a bunch carrier comprising a pair 75 of relatively movable jaws, means tending to hold said jaws closed, means for ejecting a bunch from said jaws, and means for opening said jaws while a bunch is being ejected.

12. In a cigar bunching machine in combination, a bunch carrier comprising a pair of relatively movable jaws, means tending to hold said jaws closed, means for ejecting a bunch from said jaws, and means responsive to said ejecting means for opening 85 said jaws while a bunch is being ejected.

13. In a cigar bunching machine in combination, a bunch carrier comprising a pair of relatively movable jaws, means tending to hold said jaws closed, a reciprocating 90 plunger for ejecting a bunch from said jaws, and means carried by said plunger in advance of said plunger for engaging and opening said jaws before said plunger engages the bunch between said jaws.

CLARENCE J. DU BRUL.
JOSEPH F. SEES.

Certificate of Correction.

It is hereby certified that in Letters Patent No. 1,587,478, granted June 1, 1926, upon the application of Clarence J. Du Brul, of Cincinnati, and Joseph F. Sees, of Norwood, Ohio, for an improvement in "Cigar-Bunching Machines," an error appears in the printed specification requiring correction as follows: Page 5, line 126, claim 2, after the word "claim" insert the numeral 1; and that the said Letters Patent should be read with this correction therein that the same may conform to the record of the case in the Patent Office.

Signed and sealed this 29th day of June, A. D. 1926.

[SEAL.]

M. J. MOORE,
Acting Commissioner of Patents.
